UNITED STATES PATENT OFFICE.

THOMAS EDWARD McNULTY, OF SAN FRANCISCO, CALIFORNIA.

BALLOT-BOX.

1,313,101.

Specification of Letters Patent.

Patented Aug. 12, 1919.

Application filed March 14, 1918, Serial No. 222,365. Renewed February 10, 1919. Serial No. 276,178.

To all whom it may concern:

Be it known that I, THOMAS E. McNULTY, a citizen of the United States, residing at San Francisco, in the county of San Francisco and State of California, have invented certain new and useful Improvements in Ballot-Boxes, of which the following is a specification.

This invention relates to a ballot box designed to comply with all election laws, and to afford perfect safety for the ballots, and also to permit ready and cheap repair in case the same should be accidentally broken.

The invention consists of the novel features of construction hereinafter described, pointed out in the claims and shown in the accompanying drawings, in which:—

Figure 1 is a perspective view of the box.

Fig. 2 is a vertical section, partly broken out.

Fig. 3 is a part section on the line 3—3 of Fig. 2.

Fig. 4 is an inverted perspective view of a closure plate.

In constructing the box I employ a base 1 and a top frame 2, these parts being of suitable metal. For convenience of manufacture, assembling, and repair I prefer to form these parts in octagonal form.

The top and bottom member are connected by metal vertical posts or ribs 3. As shown in Fig. 3 these ribs are vertically grooved on their adjacent faces as at 4, the grooves opening at the top of the ribs. Into these

grooves are fitted heavy glass plate panels 5. The height of the box can be varied, but in any case the panels stop short of the top. On the upper edges of the panels is placed an octagonal ring 6, having an outer depending flange 7 and an inward upwardly extending flange 8.

On said ring and inclosing the flange 8 is a glass top 9, both top or cover, and the ring being suitably cut out to span the ribs 3. The cover 9 has a rectangular mouth 10 adapted to receive a ballot. This is normally closed by a cover plate 11, flanged to fit over the cover mouth.

Within the top frame 2 is fitted a hinged

lid 12 having an opening 13 registering with 50 and corresponding in size with the cover mouth 10. Adjacent the opening the lid is undercut to engage and partially inclose the plate 11. The lid is provided with three locks, each to be operated by a separate key. 55

Should a glass panel 5 become broken the lid can be raised, the cover 9 and ring 6 lifted out, and then the broken panel removed and a new one dropped into place.

In use the keys are assigned to three officials in charge of the polling. The lid is unlocked, the plate 11 removed and the box examined. The lid is then relocked, and one of said officials is given charge of the plate 11 during the casting of the ballots. When 65 the polls close the three officers unlock the lid, the plate 11 is replaced and the box again locked. The keys are then turned over to the officer delegated by law to receive and hold them. 70

The flanged ring 6 forms a sealed joint between the cover 9 and the panels 5 and prevents the inserting of anything between the panels forming the body of the box and the cover 9 forming the top of the ballot receptacle. The ring also prevents the glass cover from coming into contact with the glass panels, thereby reducing danger of breakage in handling and shipping. 75

The advantages of this construction will 80 be obvious from the drawings and description.

What I claim is:

1. A ballot box having a metal frame, transparent panels fitting in said frame and stopping short of the top of the frame, a transparent cover arranged within the frame and fitting on said panels, a lid hinged to the frame top and covering the transparent cover, said lid and cover having alining 85 openings, and a plurality of locking devices carried by the lid. 90

2. A ballot box comprising a metal frame, glass panels removably carried by the frame, a flanged ring resting on the upper edge of the panels, a glass cover resting on said ring and having a central opening, a lid hinged to the top of the frame, and having an open- 95

ing registering with that of the cover, and a plurality of locking means carried by the lid.

3. A ballot box comprising a frame having vertically grooved ribs, panels inserted in said ribs and stopping short of the top of the frame, a cover fitting on said panels and having a central opening, a closure plate

for said opening, a lid hinged to the frame top and having an opening adapted to register with that of the cover, said lid when closed bearing on said closure plate, and means for locking the lid.

In testimony whereof I affix my signature.

THOMAS EDWARD McNULTY.

Copies of this patent may be obtained for five cents each, by addressing the "Commissioner of Patents, Washington, D. C."
